UNITED STATES PATENT OFFICE.

FREDERICK R. ELSTON, OF PHILADELPHIA, PENNSYLVANIA, ASSIGNOR TO BENJAMIN F. MILLER, OF PHILADELPHIA, PENNSYLVANIA.

WOVEN MATERIAL.

Application filed February 13, 1928. Serial No. 253,969.

This invention relates to a woven material and particularly to a material having a mottled appearance.

Instead of dyeing a material uniformly with one color or weaving a uniformly colored material with thread of a single color, it has been found desirable to produce a material having, when viewed from a distance, the appearance of uniform coloring by 5 parting thereto a mottled surface consisting of irregularly placed small patches of different colors. The appearance of this material upon close inspection is pleasing, particularly if the patches of different colors are 10 irregularly placed rather than aligned in regular pattern.

Heretofore it has been customary to produce such mottled effects either by weaving the cloth with yarn produced by twisting 20 strands of different colors whereby the colors would be visible alternately along the yarn or by weaving the cloth from undyed or uniformly colored thread and then treating with a resist and dyeing to produce irregular 25 patches of color. Either of these prior methods involves additional costly steps which increase the cost of manufacture of material of this type.

The object of the present invention is the 30 production of a fabric having the appearance described above which involves only weaving of different colored threads without requiring special yarn or special dyeing operations. More specifically the object of the present invention is the production of a fabric having incorporated by a special weave a plurality 35 of differently colored threads the numbers of which are so proportioned as to produce a pleasing mottled effect. A further object is 40 the production of such fabric without sacrificing the strength of the fabric by the use of a loose weave, the fabric forming the subject of this invention having the component threads tightly interwoven whereby a hard fabric of 45 great resistance to wear is produced.

Another object is the correlation of an arrangement of warp and weft threads of various colors with a repeat of weave to produce a repeat of design of maximum extent so that 50 the repeat of design will not be noticeable in the finished fabric.

Other more specific objects of the invention will become apparent during the following

description read in conjunction with the accompanying drawing in which:

Fig. 1 is a diagrammatic plan view of a preferred embodiment of the improved fabric illustrating one repeat of weave of warp and filler; and

Fig. 2 is a diagrammatic section through 60 the warp threads at the bottom of Fig. 1.

While it is immaterial so far as the finished cloth is concerned which threads are warp and which are filler, for convenience in disclosure the vertically arranged threads shown in Fig. 1 will be referred to as warp threads while the horizontally arranged threads will be referred to as filler threads. The warp threads shown are arranged in alternating groups of two light colored threads *a* and 65 three dark colored threads *b*. Similarly the filler threads are arranged with light colored threads *c* alternating with groups of two dark colored threads *d*. For example, the dark threads might be brown while the light 70 threads might be grey, the resulting fabric being brown, the monotone of which would be relieved by the presence of spots of grey. If it is desired to produce a light colored 75 fabric having dark spots therein the lighter 80 threads would, of course, predominate.

The repeat in the weave of both warp and weft consists of sixteen threads, the warps constituting one repeat being designated *w*₁, *w*₂ . . . *w*₁₅, *w*₁₆, and the fillers being designated *f*₁, *f*₂ . . . *f*₁₅, *f*₁₆. Warp *w*₁ as shown in Fig. 1 consists of a light thread *a* which is the first of a group of two. The last warp *w*₁₆ of the repeat also consists of a light thread *a*, the first of a group. Accordingly the first 85 warp of the next repeat to the right will consist of the second light thread *a* of a group, the first warp of the second repeat to the right will consist of the first dark thread *b* of a group, and so on. Consequently there will be 90 five repeats before the first warp again becomes the first light thread of a group. In other words the pattern will not repeat horizontally for eighty threads. Similarly, since 95 three and sixteen contain no common factor, the pattern will not repeat vertically for forty eight threads. Thus it is that a repeat of pattern measuring eighty by forty eight threads is obtainable by weaving with a repeat of sixteen threads. Because of the great 100 extent of the repeat of pattern the repeat is 105

entirely unnoticeable and the effect is cloth without any visible pattern.

While the successive repeats would normally be similar, they may be different, for example, one repeat may be the reverse of an adjacent repeat.

Any repeat of pattern within the repeat of weave is also prevented in the fabric disclosed since, it will be observed, no warp or weft follows the same course as any other warp or weft in the repeat. While the crossings may be, and as shown are, symmetrical about the center of the repeat, nevertheless, because of the prime relationship between the numbers of threads in the repeated groups of warp and filler and the sixteen threads in the repeat, the symmetry cannot be noticed in the pattern.

It is obvious that the groups of weft might be similar to the groups of warp. It is desirable, however, to have one group consist of a minimum number of threads to avoid large areas of one color.

A tight close weave is obtained because, as shown, no thread passes either over or under more than three successive threads transverse thereto.

Of the warp threads 60% are dark and 40% light. Of the filling threads 66.6% are dark and 33.3% are light. Accordingly, on the average, 63.3% of the crossings will show the dark thread while 36.6% will show light thread. While one color is made to predom-

inate in both warp and weft, it is clear that one color may predominate in warp and another in weft.

While by the arrangement shown repetition of pattern is absolutely prevented for a maximum extent of cloth, it is clear that numerous changes might be made not only to obtain the same effect but also foregoing some of the advantages while retaining others, all changes, however, being within the scope of the invention. Accordingly, the disclosure should be construed as illustrated and not as limiting the invention except within the confines of the appended claim.

Having now fully described my invention, what I claim and desire to protect by Letters Patent is:

A woven fabric comprising a set of threads consisting of successive groups each of which consists of two threads of one color and three of another color, and a second set of threads interwoven with the first set and consisting of successive groups each of which consists of one thread of one color and two of another color, the weave consisting of a repeat of weave of sixteen threads in each direction whereby a pattern having a mottled appearance is produced.

In testimony of which invention, I have hereunto set my hand, at Philadelphia, Pennsylvania, on this 7th day of Feb., 1928.

FREDERICK R. ELSTON.
